Edward M. Kojings

UNITED STATES PATENT OFFICE.

YOSHISUKE KOCHI, OF LOS ANGELES, CALIFORNIA.

SPINNING TOP.

Application filed March 9, 1926, Serial No. 93,448. Renewed June 25, 1929.

The present invention relates to improvements in spinning tops, and has for its objects to provide a top of the class herein-after described, which is well adapted to afford amusement, which will be inexpensive to manufacture, which is pleasing in appearance, and which is so formed as to retain its gyroscopic movement for an unusual length of time, and to retain the gyroscopic effect 10 to a greater degree than the ordinary spinning top.

To attain the foregoing objects and advantages, I have provided the top herein illustrated and described, having a disk-like body with a concave top surface, and having a turning peg for rotation, consisting of a straight shaft projecting downwardly from the body.

In the drawings: Figure 1 is a sectional elevation of a spinning top embodying the present invention and illustrating the form which I have so far found to be the most practical for the purpose. Fig. 2 is a top plan view of the top. Fig. 3 illustrates a 25 method of suspending the top after it has been set in motion and while it is rotating.

Referring to the drawings in detail, the body 11 consists of a disk constructed preferably from wood, having a considerable 30 diameter in proportion to its thickness, and having the concave top surface 12. The turning peg 13 projects from the bottom. In using the top, the cord 14 is first wound around the peg 13 and against the conical 35 bottom surface 15, of the body, in a spiral coil. The top is then spun in the usual way.

The advantages of my improved spinning top are attained by the novel formation of the body as shown. With the large relative 40 diameter, the weight is in the rim and through its momentum, tends to maintain the top in its rotative movement for a longer time. The primary feature is, however, in the concave top. When the top is being rotated, this formation will cause many currents of air to rush to the axial center above the top, which also tends to maintain the top in its gyroscopic movement. The top, with this concave top surface will continue 45 to rotate on its axis for a longer time than if the top surface be convex as in the ordinary top. The inrushing currents of air serve to support the rotating top in its gyroscopic plane. The top will rotate for a longer

time with the ordinary speed of movement, 55 or for the usual time with a lesser initial speed of rotation.

So persistent is the gyroscopic effect caused by the concave top surface that the top may be, after initial rotary movement in the 60 usual manner, supported by a cord as shown in Fig. 3, where it will retain its axial inclination for a considerable time. The supporting effect of the currents of air is attained only by forming the top with its 65 concave upper surface.

What is claimed is:

1. A spinning top, comprising a disk-like body, a conoidal base, a terminal peg in and projecting from the base and adapted for 70 rotation, and a smooth concave upper surface on the body, the said upper surface having a diameter in proportion to its depth as shown.

2. A spinning-top, comprising a disk-like 75 body, a conoidal base forming the lower part of the body, the inclination of the surface of the base being seventy degrees from the axis of the body, a terminal peg projecting from the base and adapted for rotation, and a 80 smooth concave upper surface on the body, the said concave surface having a diameter greater than its depth.

3. A spinning-top, comprising a disk-like body having a relatively large diameter in 85 proportion to its thickness, a terminal peg in the base for rotation, and a smooth concave upper surface on the body.

4. A spinning-top, comprising a disk-like body, a conoidal base forming the lower part 90 of the body, an axial shaft for rotation projecting from the base, and a smooth concave upper surface on the body.

5. A spinning-top, comprising a disk-like body having a conoidal base portion subtending an angle of 140 degrees, an axial shaft for rotation projecting from the body, and a smooth concave upper surface on the body, the body having a height less than its 95 diameter.

6. A spinning-top, comprising a disk-like body, a conoidal base subtending an angle of 140 degrees, an axial shaft for rotation projecting from the base, and a smooth concave upper surface on the body.

In testimony whereof, I hereunto affix my signature.

YOSHISUKE KOCHI.
